Patented Nov. 16, 1965

202,923

BRACKET

Hyman A. Klitzky, 2739 Birchwood Ave., Chicago, Ill.

Filed Jan. 12, 1965, Ser. No. 83,402

Term of patent 14 years

(Cl. D54—1)

FIGURE 1 is a perspective view of a bracket embodying my invention as viewed from the lower, rearward, left side of the bracket;

FIGURE 2 is a top plan view of the bracket;

FIGURE 3 is a bottom plan view of the bracket;

FIGURE 4 is a left side view of the bracket;

FIGURE 5 is a right side view of the bracket;

FIGURE 6 is a back view of the bracket; and

FIGURE 7 is a front view of the bracket.

I claim:

The ornamental design for a bracket, substantially as shown.
